UNITED STATES PATENT OFFICE.

BERNARD D. BEIDERHASE, OF NEW YORK, N. Y.

DESIGN FOR HANDLE OF SPOONS, FORKS, &c.

Specification forming part of Design No. 7,377, dated April 14, 1874; application filed April 4, 1874.
 [Term of Patent 7 years.]

To all whom it may concern:

Be it known that I, BERNARD D. BEIDERHASE, of New York city, in the county and State of New York, have invented a new and original Design for Spoons, Forks, &c., of which the following is a specification:

The nature of my design is fully represented in the accompanying photographic illustration, to which reference is made, and is confined to handles of spoons, forks, and ladles.

Figure 1 represents the obverse, and Fig. 2 the reverse, sides of the handle, which, in this case, is the handle of a spoon.

The handle is surrounded by a rib or border, *a*, terminating at the top end in scrolls *b*, above which is a semicircle, *c*. *d d* are indented vertical bars, curved at the top, leaving a smooth ground, *e*, between them. *f* is a flower, in the tendrils of which the bars *d d* terminate. *g* is an oblong raised surface transversely across the handle with a fan-like projection, *h*, at

each end. *i i* are raised beads, which commence in the scroll-ornament *j*, and terminate in the scroll-ornament *k*. *b* is an oblong raised transverse surface, with lateral fan-like projections *m*. Below, on a sunken surface, is an ornament, *n*, above the bowl of the spoon. The reverse side, Fig. 2, is surrounded by a border, consisting of two raised beads, *o*, with the space *p* plain from the top of the handle to the flower or leaf *q*, where the handle terminates in the bowl of the spoon. The lateral projections *h* and *m* are seen on this side of the handle.

I claim as new, and desire to secure by Letters Patent—

A spoon, fork, or ladle handle, designed substantially as shown and described.

BERNARD D. BEIDERHASE.
